(57) **CLAIM**

The ornamental design for a dual flip stand, as shown.

DESCRIPTION

FIG. 1 is a perspective view of a dual flip stand showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof in a folded state;

FIG. 10 is another perspective view thereof in a folded state;

FIG. 11 is a front view thereof in a folded state;

FIG. 12 is a rear view thereof in a folded state;

FIG. 13 is a left side view thereof in a folded state;

FIG. 14 is a right side view thereof in a folded state;

FIG. 15 is a top view thereof in a folded state; and,

FIG. 16 is a bottom view thereof in a folded state.

1 Claim, 14 Drawing Sheets
